UNITED STATES PATENT OFFICE.

PAUL MAUSER, OF OBERNDORF-ON-THE-NECKAR, GERMANY.

RECOIL-LOADING RIFLE.

No. 918,760.

Specification of Letters Patent. Patented April 20, 1909.

Application filed May 6, 1907. Serial No. 372,109.

To all whom it may concern:

Be it known that I, PAUL MAUSER, royal commercial councilor, a subject of the King of Würtemberg, Germany, and a resident of Oberndorf-on-the-Neckar, in the Kingdom of Würtemberg, German Empire, have invented certain new and useful Improvements in Recoil-Loading Rifles, of which the following is a full, clear, and exact description.

10 The present invention relates to recoil-loading rifles with sliding barrels, and more especially to the arrangement of the breech and to the locking mechanism for locking the breech bolt.

15 In a previous construction of mine, for the locking means, a block similar to a rocking cradle is provided, the upper part of which rests with its face against the rear surface of the breech bolt, and its side arms being provided with noses or projections which coact with corresponding grooves in the walls of the frame, in order to assure the compulsory movement of the block in the unlocking and locking direction.

20 In accordance with the present invention two separate movable locking and unlocking levers or arms are provided instead of this block, which levers are located on either side of the breech frame and being mounted in the barrel extension, are free to swing, whereby the compulsory adjustment of the levers or arms in the locking and unlocking positions is effected by the co-action of projections on the arms with corresponding 25 grooves in the frame or in any other part rigidly connected with the frame. The advantage of the present arrangement is that these horizontally or laterally swinging levers or arms support the breech-bolt on either side 30 symmetrically to the longitudinal axis of the breech and barrel, and further that by mounting the arms or levers laterally the whole breech system with casing can be kept lower.

45 In the accompanying drawings two arrangements of locking levers are shown constructed in accordance with the present invention, Figure 1 being an elevation partly in section, Fig. 2 a plan also partly in section, and Fig. 3 a plan showing a different position of the locking levers or arms, while Fig. 4 is a plan partly in section showing a modification. I wish it to be distinctly understood, however, that the examples shown 50 by no means limit the number of possible arrangements, but that a number of variations

in detail are possible which would still be within the scope of the invention.

In the construction shown in Figs. 1, 2 and 3, both locking levers or arms *b* are one- 60 armed levers or arms, and are pivoted on the pins *a* in the rear wall of the breech barrel extension *h*. The pins *a* are integral with the arms and project far enough into the corresponding sockets in the sides of the barrel extension, to be prevented from falling out. 65 The compulsory guidance of the levers or arms in the locking and unlocking positions, is effected by projections *c*¹ on the fore ends of the levers or arms, said projections engaging in correspondingly curved recesses *g*¹ in the upper wall of the frame *g*.

The action of the above described locking mechanism is readily understood. In the locking position (Figs. 1 and 2), the locking 75 levers or arms lie with their fore ends inclined inward in such a manner that the fore ends of the levers or arms (which are rounded off to the radius having the centers of the pins *a* as their centers) act like single- 80 arm flaps and abut against both sides of the rear surface of the breech-bolt *k* and thus support the breech-bolt in a symmetrical manner. Upon the barrel and barrel extension going back, the pins or projections 85 *c*¹ of the levers or arms in the grooves *g*¹, also slide back, the grooves being so shaped that, when the barrel extension has reached its extreme backward position, the locking 90 levers or arms will have swung out into the unlocking position, so that the breech-bolt is released and is able to pass backward between the parallel locking levers, as shown in Fig. 3.

In the construction shown in Fig. 4, the locking levers or arms *b* are not pivoted, as in the first instance, at the rear end of the barrel extension *h*, but near the center so that they act as double armed levers. The compulsory swing of the levers or arms *b*¹ *b*², for 100 the purpose of locking and unlocking, is effected by projections *c*² on the rear ends of the levers or arms *b*¹, the corresponding grooves *g*² being provided for said projections at the rear part of the wall of the frame *g*. 105

It is obvious that the principle of the mode of action of the breech or locking system effected by the examples shown, might also be attained by using other detail arrangements; for instance, the compulsory movement of 110 the locking levers or arms might be effected by other means than projections and curved

grooves, and the shape, construction and mode of mounting the locking levers or arms, could vary considerably. It is, however, always essential that the arrangement be such that the breech-bolt should be symmetrically supported at its rear surface by the shoulders of supporting mechanism (levers or arms), and that the relative supporting mechanism should be automatically moved 10 in and out, whereby the same should, when moved out, allow a free passage for the breech-bolt to pass backward.

What I claim as my invention, and desire to secure by patent is:

- 15 1. In recoil loading fire arms, the combination with a frame, a movable barrel sliding on the frame and having an extension, and a breech bolt sliding in the extension, of bolt locking levers pivoted in the rearward part 20 of the barrel extension and extending over substantially the whole length of the barrel extension and means for moving the said levers into the locking and unlocking positions.
- 25 2. In recoil loading fire arms, the combination with a frame, a movable barrel sliding on the frame and having an extension, and a breech bolt sliding in the extension, of bolt locking levers pivoted in the rearward part

of the barrel extension and extending substantially over the whole length of the barrel extension, said levers being provided with projections near their fore ends and the frame having cam slots or grooves, wherein said projections engage, the levers thus being moved like single-arm flaps and in their locking position abutting with their fore ends on both sides against the rear face of the bolt.

3. In recoil loading fire arms, the combination with a frame, a movable barrel sliding on the frame and having an extension, and a breech bolt sliding in the extension, of bolt locking levers pivoted in the rearward part of the barrel extension and provided with projections engaging in cam slots or grooves of the frame, the barrel extension having the holes for the pins of the locking levers in its rear transverse wall, and lengthwise in its side walls, cavities wherein the levers enter when swung laterally into the unlocked position.

In testimony whereof I have hereunto set my hand in presence of two subscribing witnesses.

PAUL MAUSER.
